Primary Examiner — Sanjeev Paul*Assistant Examiner* — Breana Copeland(74) *Attorney, Agent, or Firm* — Michael Best and Friedrich LLP(57) **CLAIM**

The ornamental design for a camera, as shown and described.

DESCRIPTION

FIG. 1 is a front, top, right perspective view of a camera showing my new design;

FIG. 2 is a front, top, left perspective view thereof;

FIG. 3 is a front elevational view thereof;

FIG. 4 is a left side elevational view thereof;

FIG. 5 is a right side elevational view thereof; and,

FIG. 6 is a top plan view thereof.

The broken lines illustrating portions of the camera form no part of the claimed design. The dot-dash broken lines defining boundaries of the claimed design form no part of the claimed design.

1 Claim, 6 Drawing Sheets(56)
